UNITED STATES PATENT OFFICE.

ALLISON ANDREW CLOKEY, OF RUTHERFORD, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed May 12, 1920. Serial No. 380,817.

This invention relates to signaling systems and pertains more particularly to systems of simplex telegraphy which employ positive and negative currents.

5 An object of the invention is to provide a telegraph system of the above character having means for rendering it possible while a message is being transmitted between two stations, for a receiving operator to instantly 10 break the transmitting circuit and reverse the direction of sending.

Another object is the provision of means, operative when it is desired to reverse the direction of sending, for reversing the relation 15 of the transmitting and receiving apparatus with respect to the line.

For accomplishing the above objects, the invention provides, at each of the stations, a pair of relays arranged in conjunction 20 with the transmitting and receiving apparatus, whereby, when a current impulse of predetermined polarity and duration is transmitted over the line, these relays will respond to reverse the relation of the transmitting and receiving apparatus at each of 25 the stations with respect to the line.

The drawing shows a Wheatstone transmitter and only so much of the system as is necessary for a clear understanding of the 30 invention.

The transmitter 4 comprises a pair of contact operating levers 6 and 7, which are revolvably mounted on a member 8. Pivoted at one end of each of these levers are pins, 9 35 and 10 respectively, which are designed to cooperate with a tape 5, in which perforations are arranged in such a manner that the impulses composing a message may be properly transmitted over the line. In order that the pins 9 and 10 may be withdrawn after 40 they have passed through perforations in the tape, a cam mechanism is provided. This cam mechanism comprises a shaft 11, which is driven by means of a motor 12. 45 The shaft of the motor is connected with the shaft 11 by means of a friction clutch, such as shown at 13. Upon the shaft 11, there is secured a series of cams 14, 15 and 16. The first two of these cams are mounted in close 50 proximity to the levers 6 and 7 and serve to withdraw the pins 9 and 10 whenever they pass through a perforation in the tape 5.

The other of these cams operates a lever 17, to which there is secured a stepping pawl 18. This stepping pawl 18 is arranged to engage the teeth of a ratchet wheel 19, keyed 55 to a shaft 20. At one end of this shaft 20 is a star wheel 21, which engages a series of feed holes in the tape 5 and serves to effect the advancement of the tape for each revolution of the cam 16. There is also secured to the shaft 11, an arm 22 which is adapted to be engaged by a latch 23 under the control of a magnet 24.

The levers 6 and 7 upon being actuated, 65 due to the passage of the pins attached to the end thereof through holes in the tape 5, cause the connection of a source of battery with a conductor 25, to which there is serially connected a pair of polarized relays 26 and 27, respectively. These relays control the application of a source of signaling current to line 28 in accordance with the actuation of the levers 6 and 7. Both of these relays have their armatures biased in such a manner as to normally engage the left-hand contact. The first of these relays, however, is designed to respond to current impulses of a negative polarity, while the other responds to current impulses of a positive polarity. In this way current impulses of different polarities may be impressed on the line 28, which extends to a distant station 70 (not shown) where equipment like that illustrated in the drawing is to be understood as being present.

There is also connected to the line 28, a pair of polarized relays 29 and 30 respectively, which are designed to respond to current impulses impressed on the line through 75 the actuation of a pair of rotary keys 31 and 32. Relay 29 is arranged in such a manner that a receiving instrument, as indicated by the numeral 33, is normally connected with the line 28 through a sending 80 condenser 34. Although no specific form of recording mechanism has been shown, any of the well-known types of recorders may be used, such as the Siphon recorder, etc. Upon the energization of relay 29 by a current impulse of a polarity opposite to that which 85 previously traversed its windings to position the armature thereof as shown in the drawing, the armature thereof will be positioned 100

to disconnect the receiving instrument 33 from the line and connect the transmitting apparatus connected thereto. It is thus seen that the connection and disconnection of the 5 receiving and transmitting apparatus to and from the line, is controlled through the contacts of relay 29.

Relay 30 controls through its contacts the energization of magnet 24, which, as previously described, controls the actuation of the 10 latch 23 for causing the engagement thereof with the arm 22 and in turn the stopping of the shaft 11. In order that the polarized relays 29 and 30 will not be affected by the transmission of the message 15 impulses, an impedance coil 35 is connected intermediate the line 28 and the windings of relays 29 and 30. This impedance coil 35 offers a high impedance to current impulses 20 of signaling frequencies, but is of relatively low impedance to unvarying direct current applied to the line due to the actuation of either of the keys 31 and 32.

The operation of the system is as follows: 25 Let it be assumed that a message is being transmitted from a distant station over the line 28. The impulses incoming from the distant station will therefore traverse the condenser 34, the left-hand contact of relay 30 29, and the receiving instrument 33 to ground. It is, of course, understood that the 30 transmission of the impulses composing the message is effected by means of transmitting apparatus similar to that shown in the 35 lower portion of the figure of the drawing, and inasmuch as the operation of such apparatus is well known to telegraph experts, and especially since it does not form a part of the present invention, a further description 40 thereof is considered unnecessary.

If the operator at the receiving station desires for any reason to break the transmitting operator and reverse the direction of sending, the key 31 would be caused to rotate 45 in the direction indicated by the arrow. The actuation of key 31 in this manner impresses on the line 28, through the windings of the relays 29 and 30 and the impedance coil 35, an impulse of a positive polarity, and 50 of such duration as to permit the current in the line at the distant station to rise to its final steady value. This impulse, incoming at the station which was previously transmitting, traverses the windings of relays 30 and 29, which causes the movement of the 55 armatures controlled thereby. Relay 30 in operating closes the circuit including the winding of the magnet 24, which is thereupon energized. The magnet 24 in operating 60 causes the engagement of the latch 23 with the arm 22, which, as previously brought out, is secured to the shaft 11. The engagement of the latch 23 with the arm 22 stops the transmitting mechanism.

There is also connected in circuit with the magnet 24, an alarm device 36 which is designed to be sounded upon the closure of the left-hand contact of relay 30. During the period that a particular station is receiving, this alarm device may be short-circuited by 65 means of a key 37. The sounding of this alarm serves as an indication to the transmitting operator that the transmitting mechanism has been stopped, due to the transmission of an impulse from the receiving station. Relay 29 at this station, having been 70 previously energized in such a manner as to effect the closure of its right-hand contact, which connects the armature of the transmitting relay 27 with the line, is at this instant energized by the current impulse impressed on the line, through the actuation of key 31 at the receiving station for closing its left-hand contact. The closure of the left-hand contact of this relay connects the receiving network therewith the line 28. At the receiving station, the reverse is however true. That is, relay 29 is energized for opening its left-hand contact and closing its right-hand contact. The closure of the right-hand contact thereof connects the armature of relay 27 with the line 28. Relay 30 in operating opens its left-hand contact, thereby breaking the energizing circuit for the magnet 24. The deenergization of magnet 24 allows the latch 23 to disengage the arm 22, whereupon the shaft 11 is revolved by the motor 12. If a tape is at this instant in position, message impulses will be transmitted 85 over the line in accordance with the perforations in the tape.

When the operator at the station which was originally receiving the message, desires to again associate the receiving apparatus therewith the line, he actuates key 32. The actuation of this key applies an impulse of polarity opposite to that which was previously applied, through the actuation of the key 31, to the line, thereby causing the positioning of the armatures, controlled by relays 29 and 30, in such a manner as to connect the receiving network with the line and to disconnect the transmitting apparatus from the line. At the original transmitting station, the relays corresponding with relays 29 and 30, have their armatures so positioned that the receiving instrument 33 is disconnected from the line and the transmitting mechanism is permitted to transmit the remaining portion of the message. It is thus seen from the previous description that the invention provides means whereby a receiving operator may instantly break a transmitting operator and reverse the direction of sending with great rapidity.

From the foregoing description it is seen that relays 29 and 30 are of the type known in the art as unbiased non-centered polar

relays. The armature of a relay of this type remains in whichever position the last energizing impulse of current caused it to assume regardless of the fact that the energizing current has ceased to flow.

5 Although the invention has been shown and described in connection with a telegraph system of the simplex variety, it is not intended to limit the invention to this particular use, as it is obvious that it may be used 10 in connection with other telegraph or signaling systems without departing from the spirit and scope of the invention.

What is claimed is:

15 1. A line, transmitting and receiving apparatus at each terminal of said line and means for changing the electrical connection of said transmitting and said receiving apparatus at both terminals to effect a change 20 in the direction of transmission, said means including a switch at each terminal for controlling circuits from said line to said receiving and transmitting apparatus respectively, one of said circuits being opened at 25 said switch when the other is closed at said switch, relay means controlling said switch, and at all times responsive to line current 30 of character different from the signaling current, and means at each terminal operative at all times for affecting said relay means at both terminals substantially simultaneously and independently of energy of signals.

2. A line, transmitting and receiving apparatus at each terminal of said line and means for changing the electrical connection of said transmitting and said receiving apparatus at both terminals to effect a change 35 in the direction of transmission, said means including a switch at each terminal for controlling circuits from said line to said transmitting and said receiving apparatus respectively, one of said circuits being opened at 40 said switch when the other is closed at said switch, relay means at each terminal operative at all times for causing said switches to 45 operate substantially simultaneously in opposite directions at said terminals, and means at each terminal for controlling both said 50 relay means.

3. A line, transmitting and receiving apparatus at each terminal of said line and means for changing the electrical connection of said transmitting and said receiving apparatus at both terminals to effect a change 55 in the direction of transmission, said means including switching means at each terminal for controlling circuits from said line to said receiving and transmitting apparatus respectively, one of said circuits being opened 60 when the other is closed, means including said switching means for impressing current of either polarity at will upon said line, relay means at said terminals responsive to 65 current of one polarity for causing one of

said switches to associate the transmitter at that terminal with said line and the other of said switches to associate the receiver at that terminal with said line and responsive to current of the opposite polarity for reversing these connections.

4. A signaling system comprising a line extending between two stations, receiving and transmitting apparatus at each of said stations, means responsive to a current impulse for automatically reversing the relation of said receiving and transmitting apparatus at both stations with respect to said line and means for causing the transmitter thus associated with the line to initiate the 70 transmission of signals independently of an operator.

5. A signaling system comprising a line extending between two stations, receiving and transmitting apparatus at each of said stations, and unbiased non-centered polar relays at said stations respectively responsive to a current impulse for automatically reversing the relation of said receiving and transmitting apparatus with respect to said 85 line.

6. Means for changing the direction of transmission over a signaling line comprising means at each terminal for initiating transmission of current for controlling the 90 association of transmitter and receiver at both terminals with the line independently of signal currents and of the operator at the other station and without the operation of corresponding means at the other terminal for initiating transmission of control current.

7. The method of changing the direction of transmission over a signaling line and initiating signaling thereover in the reverse 105 direction which comprises controlling the connection of the transmitter and receiver to the line at both terminals from each terminal and controlling the starting of each transmitter at each terminal independently 110 of the operator at the other terminal whereby the transmission of signals to the controlling terminal from the controlled terminal may be initiated independently of the operator at the controlled terminal.

8. A telegraph system comprising a pair of terminal stations interconnected by a transmission line, each of said stations including a receiving mechanism, a transmitting mechanism, and an auxiliary transmitting mechanism cooperating with the transmitting mechanism to reverse the direction of transmission over the line.

9. A telegraph system comprising a pair of terminal stations interconnected by a 125 transmission line, each of said stations including a receiving mechanism, a transmitting mechanism, an auxiliary transmitting mechanism, and means cooperating with the auxiliary transmitting mechanism for con- 130

trolling the direction of transmission over the line.

10. A telegraph system comprising a pair of terminal stations interconnected by a transmission line, each of said stations including a receiving mechanism, a transmitting mechanism, an auxiliary transmitting

mechanism, and a selective mechanism under the control of the auxiliary transmitting mechanism for controlling the direction of ¹⁰ transmission over the line.

In witness whereof, I hereunto subscribe my name this 10th day of May A. D., 1920.

ALLISON ANDREW CLOKEY.
